UNITED STATES PATENT OFFICE.

EUGÈNE SCHNEIDER, OF PARIS, FRANCE, ASSIGNOR TO SCHNEIDER & CIE., OF PARIS, FRANCE, A LIMITED JOINT-STOCK COMPANY OF FRANCE.

APPARATUS FOR PRODUCING HOOPING EFFECTS IN METAL TUBES.

Application filed October 29, 1920. Serial No. 420,523.

To all whom it may concern:

Be it known that I, EUGÈNE SCHNEIDER, a citizen of the Republic of France, and resident of Paris, France, have invented new 5 and useful Improvements in Apparatus for Producing Hooping Effects in Metal Tubes, which invention is fully set forth in the following specification.

The present invention consists of improvements on an earlier invention for 10 which a patent has been granted and numbered 1,338,872, wherein there is described an apparatus for producing hooping effects in metal tubes by successive zones by means 15 of a liquid forced under pressure into the annular space between the internal wall of the tube to be hooped and a hooping mandrel.

The apparatus described in the said 20 earlier patent comprises a device for producing by a gradual displacement of the hooping mandrel, a gradual increase of the pressure in the annular space; the said displacement being automatically limited by a 25 discharge of the liquid confined in the said space through a duct closed by a loaded valve, the load on the valve being automatically regulated according to a determined law, and this regulation being effected by a 30 mechanism controlled simultaneously by the displacement of the mandrel and by a guiding means.

In the constructional form described in 35 the aforesaid earlier patent, the discharge of the liquid takes place through an axial passage in the mandrel, said passage opening into a discharge duct formed in an outer extension of the said mandrel, the loaded valve being situated at the outlet thereof.

40 The hooping of tubes of great length requires of course a mandrel of corresponding length which is difficult to provide in one piece. Consequently it is necessary to make the mandrel in at least two sections connected 45 together by a joint. At the moment when these joints pass out of the tube to be hooped, leakages of the liquid under high pressure are almost unavoidable.

The present invention has for its object 50 to provide an improved construction of the earlier invention that allows of obviating this first drawback.

The improved construction comprises also various other improvements, and more par-

ticularly a device for guiding the outer end 55 of the mandrel in its exit from the tube. The accompanying drawings illustrate a practical example of the improved construction.

Complementary Figs. 1, 1^a are a longitudinal sectional elevation of the general arrangement, taken through the axis of the tube that is being subjected to the hooping operation.

Complementary Figs. 2, 2^a are a similar 60 detail sectional elevation illustrating the device for discharging the liquid and for regulating the load on the valve.

Figs. 3 and 4 are sections respectively on the lines III and III, IV and IV of Fig. 2^a. 70

Fig. 5 is a section on the line V—V of Fig. 1.

Fig. 6 is a section on the line VI—VI of Fig. 2.

In these figures, A is the tube to be hooped, 75 resting upon suitable supports B; C is the hooping mandrel engaged in the tube. The liquid under pressure is confined in the annular space F comprised between the inner wall of the tube A and the surface of the 80 mandrel C, this space being limited by a fixed end joint D and a head joint E movable with the mandrel.

According to the present invention, the discharge of the liquid, instead of taking 85 place, as in the constructional form described in the aforesaid earlier patent, through an axial duct formed in the mandrel C, now takes place through a duct a formed in the tube A close to the end of the latter, through which the mandrel passes out. The result is that the loaded valve which normally closes the said duct, is lodged in a box a¹ arranged in a recess formed in the end of the tube A. This 95 valve may, as in the examples described in the aforesaid earlier patent, be constituted by a ball G pressed upon its seat by a finger H under the action of a lever I which is fulcrumed on a support J that is likewise 100 attached to the tube A. On this lever I there is adapted to slide a weight K, the load on the valve varying according to the position occupied by the said weight on the lever. It will be readily perceived that 105 whatever may be the position occupied by the mandrel during the hooping operation, no leakage of liquid is to be feared through

the joint or joints between the sections of the mandrel, and further that the mandrel is not weighted at its free end by the device that regulates the load on the valve, since 5 the said device is supported partly by the tube and partly by the rear crosshead X^1 .

The connecting device between the mandrel and the load on the valve, has been modified in the new constructional form, as 10 follows:—

Upon the rear crosshead X^1 which by its connection with the front crosshead X by means of the rods Y , maintains the tube A in position for hooping, there is fixed a support M carrying bearings m in which an endless screw L is journalled. On this screw a nut k is adapted to move which is provided with arms in the form of a fork k^1 in which the weight K slipped on the rod I , 15 rests by means of studs K^1 . The nut k is suitably guided in the support M (Fig. 6).

On the extension of the endless screw L there is fixed a pinion L^1 connected by a chain L^2 to a toothed wheel L^3 fixed on a 20 shaft p which is journalled in bearings carried by the support P of the slotted guide O , the slot in said guide being inclined from one end of the guide to the opposite end thereof. A gear connects the shaft p to the hooping 25 mandrel C . This gear comprises for example a rack N carrying at its upper end an axle-pin n^1 guided in slots formed in side members n^1 fixed to a sleeve n^2 which is slipped upon the outer end of the mandrel 30 C and is fixed to the latter by bolts n^9 . The said rack N carries at its lower end a roller n engaged in the slot O . With the rack N there meshes a pinion N^1 mounted on shaft N^2 journalled in the support of P , and 35 carrying on its front end a toothed wheel N^3 meshing with a pinion N^4 fixed on the shaft p .

Since the shaft N^2 has a length corresponding to that of the longest tubes to be 40 hooped, it is necessary to provide it with intermediate bearings; but these bearings must be constituted in a special manner so as to allow the sliding pinion N^1 to pass freely in its movements along the shaft.

According to the present invention the 45 said bearings are constituted by troughs 1 forming one of the sides of a jointed parallelogram, the opposite side being formed by a projection 2 of the support P . The vertical sides 3 of the jointed parallelogram are extended beyond their lower pivot by counterweights 4. The pinion N^1 is held 50 in a box n^5 fixed to a support or carrier N^6 on which is formed the sleeve n^2 . All exit 55 of the mandrel C due to the liquid under pressure acting upon the front end of the hooping mandrel, will produce a displacement 60 of the support N^5 . When the box n^5 meets one of the intermediate bearings 1 65 which has entrance ramps at its ends (Fig.

1), it will cause a tipping of the arms 3, 3 to which the bearing is jointed, and it will bring them into the position indicated in dot and dash lines in Fig. 1.

As soon as the pinion has moved beyond 70 the end of the bearing, the latter will be caused by the action of the counterweights 4 to resume its position of rest shown in full lines.

The rack N which is compelled to follow 75 the slotted guide O in which the roller n is engaged, rises and falls according to the position assumed by the said roller. In these vertical movements the said rack actuates the pinion N^1 which transmits in its 80 turn the motion through the shaft N^2 , the toothed wheel N^3 and the pinion N^4 , to the shaft p , and consequently to the wheel L^3 , and through the latter to the chain L^2 and pinion L^1 . The screw L is thus actuated, 85 and, by its rotation, causes a longitudinal displacement of the nut k driving the weight K .

In practice it is advisable to make the sleeve n^2 adjustable as to height relatively 90 to the sliding support or carrier N^5 for the purpose of obviating any deflection of the hooping mandrel or of the shaft N^2 in the case of a want of parallelism between their axes. As a matter of fact a bending strain 95 upon the mandrel C would have the drawback of destroying the tightness of the fixed joint D . As shown in Fig. 3, the sleeve n^2 rests on the slide block or carrier N^5 through the medium of a cradle N^6 bearing 100 with its inclined lower faces n^8 upon wedges N^7 that are capable of sliding by means of an internal screwthread on screw-threads n^8 of opposite hands formed on an axle N^9 journalled in the said slide block 105 N^5 , and to which rotational motion can be imparted by means of a crank N^9 . By turning the latter in the desired direction, the wedges N^7 are moved nearer to or away 110 from each other, thereby producing the rising or falling movement of the cradle N^6 , and consequently of the mandrel C resting on it.

Having now particularly described and ascertained the nature of my said invention 115 and in what manner the same is to be performed, I declare that what I claim is:—

1. In an apparatus of the character described, a movable mandrel projecting through one end of the tube being treated 120 and having a head at its opposite end, a duct formed in said tube near the end through which the mandrel projects, a loaded valve in said duct, guide means supported independently of said tube, mechanism engaging 125 said guide means and actuated by the mandrel on movement thereof, and means controlled by said mechanism for automatically regulating the load of said valve.

2. In an apparatus of the character de- 130

- scribed, a movable mandrel projecting through one end of the tube being treated and having a head at its opposite end, a loaded valve in the end of the tube through which the mandrel projects, an endless screw, a nut movable along said endless screw by rotation of the latter and carrying the load of said valve, guide means supported independently of said tube and provided with an inclined slot, a shaft journaled on the support for said guide means, mechanism actuated by the mandrel on movement thereof for imparting motion to said shaft, said mechanism including a pinion splined to the shaft for movement longitudinally thereon and a rack meshing with the pinion and provided with a roller engaging said inclined slot, and means whereby said nut is moved to regulate the load of said valve, said means comprising gears keyed to the shaft and endless screw respectively, and an endless chain engaging the teeth of said gears.
3. In an apparatus of the character described, a movable mandrel projecting through one end of the tube being treated and having a head at its opposite end, a loaded valve in said tube near the end through which the mandrel projects, guide means supported independently of the tube and provided with an inclined slot, a shaft journaled on the support for said guide means, mechanism actuated by the mandrel on movement thereof for imparting motion to said shaft, said mechanism including a gear splined on the shaft for movement longitudinally thereon and a rack meshing with said gear and provided with a roller engaging said inclined slot, bearings for said shaft disposed intermediate the ends thereof and pivotally mounted on said support to provide for movement of the gear along the shaft, and means imparting motion of said shaft to the load of said valve for automatically regulating the same.
4. In an apparatus of the character described, a movable mandrel projecting through one end of the tube being treated and having a head at its opposite end, a loaded valve in the tube near the end through which the mandrel projects, guide means supported independently of the tube, a shaft journaled on the support for said guide means, mechanism for imparting motion to said shaft, said mechanism engaging the guide means and being actuated by said mandrel on movement thereof, means for automatically regulating the load of said valve and controlled by the motion of said shaft, and means for regulating the distance between said mandrel and the shaft, said regulating means comprising a carrier movable along said support, a cradle attached to said carrier and supporting the projecting end of said mandrel and relatively adjustable wedges between the carrier and cradle.
5. In an apparatus of the character described, a closure for one end of the tube being treated, a mandrel axially movable within the tube and having one end projecting through said closure, a head secured to the opposite end of said mandrel, said mandrel and tube providing an annular chamber to contain the deforming fluid, a duct in the tube adjacent to said closure and providing for discharge of fluid from the chamber as said head advances, and means controlling the flow of fluid through said duct.
6. In an apparatus of the character described, a closure for one end of the tube being treated, a mandrel axially movable within said tube and having one end projecting through said closure, a head secured to the opposite end of said mandrel, said mandrel and tube providing an annular chamber to contain the deforming fluid, a duct in the tube adjacent to said closure and providing for discharge of fluid from the chamber as said head advances, a loaded valve controlling the flow of fluid through said duct, and mechanism for varying the load of said valve.
7. In an apparatus of the character described, a closure for one end of the tube being treated, a mandrel axially movable within said tube and having one end projecting through said closure, a head secured to the opposite end of said mandrel, said mandrel and tube providing an annular chamber to contain the deforming fluid, a duct in the tube adjacent to said closure and providing for discharge of fluid from the chamber as said head advances, a loaded valve controlling the flow of fluid through said duct, and mechanism supported independently of the mandrel for varying the load of said valve.
8. In an apparatus of the character described, a closure for one end of the tube being treated, a mandrel axially movable within the tube and having one end projecting through said closure, a head secured to the opposite end of said mandrel, said mandrel and tube providing an annular chamber to contain the deforming fluid, a duct formed in the tube adjacent to said closure and providing for discharge of fluid from the chamber as said head advances, a valve in said duct for controlling flow of the fluid therethrough, load mechanism mounted on the tube support for automatically regulating the movement of said valve, and mechanism supported independently of the mandrel for operating said load mechanism and actuated by movement of said mandrel.
9. An apparatus for producing hooping effects in metal tubes by the compression of fluid therein including a mandrel axially movable in the bore of the tube being treated.

ed, in combination with a support adapted to carry the end of the mandrel leaving the tube, said support being movable in parallel relation to the axis of the tube and operating to maintain the mandrel in axial alinement with the bore of the tube.

10. An apparatus for producing hooping effects in metal tubes by the compression of fluid therein including a mandrel axially movable in the bore of the tube being treated, in combination with a vertically adjustable support adapted to carry the end of the mandrel leaving the tube, said support being movable in parallel relation to the axis 15 of the tube and operating to maintain the mandrel in axial alinement with the bore of the tube.

11. An apparatus for producing hooping effects in metal tubes by the compression of fluid therein including a mandrel axially movable in the bore of the tube being treated, in combination with a guide-way in parallel relation to the axis of the tube and having a support movable thereon adapted 25 to carry the end of the mandrel leaving the tube, said movable support operating to maintain the mandrel in axial alinement with the bore of the tube.

12. An apparatus for producing hooping effects in metal tubes by the compression of fluid therein including a mandrel axially movable in the bore of the tube being treated, in combination with a guide-way in parallel relation to the axis of the tube and having a support movable thereon provided 35 with a vertically adjustable member adapted to carry the end of mandrel leaving the tube, said movable support and vertically adjustable member operating to maintain 40 the mandrel in axial alinement with the bore of the tube.

13. An apparatus for producing hooping effects in metal tubes by the compression of fluid therein including a mandrel axially movable in the bore of the tube being treated, in combination with means adapted 45 to support the end of the mandrel leaving the tube, said means operating to maintain the mandrel in axial alinement with the bore 50 of the tube and comprising a guide-way having a slide movable thereon, and a cradle vertically adjustable on the slide to carry the outer end of the mandrel.

14. An apparatus for producing hooping effects in metal tubes by the compression of fluid therein including a mandrel axially movable in the bore of the tube being treated, in combination with means adapted 55 to support the end of the mandrel leaving the tube, said means operating to maintain the mandrel in axial alinement with the bore of the tube and comprising a guide-way having a slide movable thereon, a cradle mounted on the slide to carry the outer end 60 of the mandrel, and relatively adjustable

wedges between the slide and cradle providing for vertical adjustment of said cradle on said slide.

15. An apparatus for producing hooping effects in metal tubes by the compression of fluid therein including a mandrel axially movable in the bore of the tube being treated, in combination with means adapted to support the end of the mandrel leaving the tube, said means operating to maintain the mandrel in axial alinement with the bore of the tube and comprising a guide-way having a slide movable thereon, a cradle mounted on the slide and carrying a sleeve displaceably mounted on the outer end of the mandrel, and means for vertically adjusting the cradle on the slide.

16. In combination, a tube, a member axially movable within the tube, a loaded valve in the wall of said tube, and means actuated by said movable member for varying the load of said valve.

17. In combination, a tube, a mandrel axially movable within said tube, a duct in the wall of said tube, a loaded valve in said duct, guide means, mechanism cooperating with said guide means and actuated by said mandrel on movement thereof, and means controlled by said mechanism for automatically regulating the load of said valve.

18. An apparatus of the character described, including a mandrel axially movable within the tube being treated and projecting from one end thereof, a head secured to said mandrel, a duct formed in the tube remote from the initial position of said head, and a loaded valve in said duct for controlling the flow of fluid therethrough as said head advances, in combination with mechanism for varying the load of said valve, a member provided with an inclined slot, an element mounted on the projecting end of the mandrel for movement therewith and engaging said inclined slot, and mechanism operating by the movement of said mandrel and element to actuate said load-varying mechanism.

19. An apparatus for producing hooping effects in metal tubes, including a mandrel axially movable within the tube being treated, a head secured to said mandrel, a duct formed in the tube remote from the initial position of said head, and a loaded valve in said duct for controlling flow of fluid therethrough as said head advances, in combination with a rack slidably mounted on the projecting end of said mandrel, means imparting sliding movement to said rack as the mandrel advances, a shaft extending in parallel relation with the axis of said mandrel, means for imparting rotation to said shaft actuated by the sliding movement of said rack, said means comprising a pinion splined on the shaft to move longitudinally thereon and engaged by the rack, and means

115

120

125

130

transmitting rotative movement of the shaft to said valve load-varying mechanism.

20. An apparatus for producing hooping effects in metal tubes, including a mandrel axially movable within the tube being treated, a head secured to said mandrel, a duct formed in the tube remote from the initial position of said head, and a loaded valve in said duct for controlling flow of fluid therethrough as said head advances, in combination with load mechanism for said valve comprising a lever connected with the valve, an endless screw, a weight engaged by said endless screw and movable along the lever by rotation of the screw, and means actuating said mechanism to vary the load on said valve and made effective by movement of the mandrel, said means comprising a sleeve detachably secured on the projecting end of the mandrel, a guide member provided with an inclined slot, a rack slidably mounted on said sleeve and receiving motion by engagement thereof with said inclined slot, a shaft extending in parallel relation with the axis of said mandrel, a pinion splined on said shaft to move longitudinally thereon and imparting rotation to the shaft by engagement with said rack, and gearing for transmitting rotative movement of the shaft to said endless screw.

21. An apparatus for producing hooping effects in metal tubes, including a mandrel axially movable within the tube being treated, a head secured to said mandrel, a duct formed in the tube remote from the initial position of said head, and a loaded valve in said duct for controlling flow of fluid therethrough as said head advances, in combination with mechanism for varying the load of said valve, said mechanism including a shaft extending in parallel relation with the axis of said mandrel and a pinion splined to the shaft for movement longitudinally thereon, a rack slidably mounted on the projecting end of the mandrel to move therewith and engaging said pinion, means coupling the rack with said pinion to provide for constant engagement therebetween, means actuating said rack and pinion as the mandrel advances thereby imparting rotation to said shaft, and means transmitting rotative movement of the shaft to the valve load-varying mechanism.

22. An apparatus for producing hooping effects in metal tubes, including a mandrel axially movable within the tube being treated, a head secured to said mandrel, a duct formed in the tube remote from the initial position of said head, and a loaded valve in said duct for controlling flow of fluid therethrough as said head advances, in combination with a guide way having substantially parallel relation with the mandrel axis, a support movable on the guide way and carrying the projecting end of the man-

drel, a shaft having parallel relation with the guide way, a pinion splined to the shaft for movement longitudinally thereon, a rack slidably mounted on the projecting end of the mandrel and engaging said pinion, means actuating said rack and pinion as the mandrel advances thereby imparting rotation to said shaft, means holding the rack and pinion in engagement during the advancing movements of the mandrel and its support, and means imparting rotative movement of the shaft to said valve load-varying mechanism.

23. An apparatus of the character described, including a mandrel axially movable within the tube being treated, a head secured to said mandrel, a duct formed in the tube remote from the initial position of said head, and a loaded valve in said duct for controlling flow of fluid therethrough as said head advances, in combination with mechanism transmitting motion of the mandrel to the valve for varying the load thereof, said mechanism including a shaft and an element driving said shaft by rotation therewith and movement longitudinally thereon, and means supporting said shaft at a point intermediate the ends thereof and movable by said element to prevent interference with longitudinal motion of the latter along the shaft.

24. An apparatus of the character described, including a mandrel axially movable within the tube being treated, a head secured to said mandrel, a duct formed in the tube remote from the initial position of said head, and a loaded valve in said duct for controlling flow or fluid therethrough as said head advances, in combination with mechanism transmitting motion of the mandrel to the valve for varying the load thereof, said mechanism including a shaft and an element driving said shaft by rotation therewith and movement longitudinally thereon, means supporting said shaft at a point intermediate the ends thereof and movable by said element to prevent interference with longitudinal motion of the latter along the shaft, and means normally maintaining said supporting means in engagement with said shaft and adapted to re-establish said engagement when said element has traveled beyond said supporting means.

25. An apparatus of the character described, including a mandrel axially movable within the tube being treated, a head secured to said mandrel, a duct formed in the tube remote from the initial position of said head, and a loaded valve in said duct for controlling flow of fluid therethrough as said head advances, in combination with mechanism transmitting motion of the mandrel to the valve for varying the load thereof, said mechanism including a shaft and an element driving said shaft by rotation there-

with and movement longitudinally thereon, and a movable auxiliary support for said shaft disposed at a point intermediate the ends thereof, said support comprising a plurality of pivoted levers provided with weights at their lower ends and a trough connected to their upper ends for normal engagement with the under side of the shaft, said driving element operating to depress

the trough clear of the shaft and said weights operating to establish supporting engagement of the trough with the shaft.

In testimony whereof I have signed this specification.
